APPARATUS FOR PICKLING PLATES

Charles G. Watson, Youngstown, Ohio, assignor
to The Youngstown Welding & Engineering
Company, Youngstown, Ohio, a corporation of
Ohio

Application September 25, 1947, Serial No. 776,078

13 Claims. (Cl. 51—163)

1

This invention relates to an apparatus for pickling plates, sheets, or the like.

One of the principal objects of the invention is the provision of a novel and improved apparatus for simultaneously pickling a plurality of sheets or plates, which apparatus assures contact of the entire surfaces of the sheets or plates with the pickling solution and can be assembled from readily available, inexpensive equipment.

Another object of the invention is the provision of a novel and improved apparatus of the character referred to wherein a plurality of sheets or plates are supported on edge by a flat or straight surface and caused to tilt through a limited movement relative to said surface whereby the adjoining sides of adjacent sheets or plates are moved slightly relative to each other, thus facilitating the penetration of the pickling liquid between the sheets or plates and the removal of scale therefrom.

Another object of the invention is the provision of a novel and improved apparatus for pickling plates or the like, which apparatus comprises a substantially straight surface upon which a plurality of plates are adapted to be supported on edge for limited tilting movement, in combination with means for causing the plates to tilt on said supporting surface and the adjoining sides of adjacent plates to move relative to each other.

Further objects and advantages of the invention will be apparent to those skilled in the art to which it relates from the following description of the preferred apparatus described with reference to the accompanying drawings forming a part of this specification in which similar reference characters designate corresponding parts, and in which

Fig. 1 is a plan view of the present preferred form of a pickling apparatus embodying the present invention;

Fig. 2 is a sectional view, approximately on the line 2—2 of Fig. 1 and showing plates to be pickled in place in the apparatus;

Fig. 3 is a sectional view, approximately on the line 3—3 of Fig. 1;

Fig. 4 is a plan view of a modified form of a pickling apparatus embodying the present invention with the crate or framework for supporting the plates to be pickled removed;

Fig. 5 is a sectional view, approximately on the line 5—5 of Fig. 4, and showing plates to be pickled in place in the apparatus;

Fig. 6 is a fragmentary side elevational view, on an enlarged scale, of the drive mechanism for the two forms of the apparatus illustrated in Figs. 1 to 5;

2

Fig. 7 is a fragmentary end elevational view of one of the crates of the apparatus in one of its tilted positions and illustrating the resulting positions of the plates therein; and

Fig. 8 is a view similar to Fig. 7 but with the crates of the apparatus in another of its tilted positions and illustrating the resulting positions of the plates therein.

Referring first to Figs. 1 to 3 of the drawings, which illustrate the present preferred form of the apparatus, the reference character A designates a tank which may be of any conventional construction and made of any suitable material resistant to the pickling solution with which it is filled substantially to the top. The tank shown is of elongated, rectangular shape in plan view, as is the usual practice. The tank per se forms no part of the present invention and is not herein described in detail. The tank A is provided with a cradle B made of Monel metal or some other suitable material resistant or inert to the pickling solution and adapted to carry two crates C hereinafter described. The cradle comprises a plurality of transversely extending members 10 suspended by vertically extending members 11, 12 at opposite sides of the tank. Four transversely extending members 10 are shown but it is to be understood that a greater number may be used depending upon the length of the tank and the construction of the crates or frameworks herein-after referred to, which support the plates to be pickled and are, in turn, supported by the cradles. Opposite ends of the members 10 are pivotally connected to the members or rods 11, 12 as by pins 13. The upper ends of the members or rods 11, 12 are pivotally connected by pins 14 to arms 15, 16, respectively, which are in turn fixed to longitudinally extending shafts 17, 18. These arms extend inwardly toward the longitudinal centerline of the tank so that the members or rods 11, 12 are substantially vertical when the members 10 are horizontal. The longitudinally extending shafts are rotatably supported in suitable bearing brackets 20 bolted or otherwise secured to supports or pillars 21 at opposite sides of the tank. In the present instance the supports 21 are shown as concrete piers; however, other constructions may be employed or the shafts may be supported on the tank proper. With the preferred arrangement, the tank A can be replaced without disturbing other parts of the equipment.

The plates or sheets P to be pickled are supported in upstanding relationship by crates or frameworks C which are adapted to be readily immersed in the pickling solution in the tank and

to be removed therefrom. As shown, there are two crates or frameworks C but a single crate or framework may be employed if the plates P are of great length. When a crate or framework is in the tank it rests upon one or more of the members 10 of the cradle B and is rocked and lifted thereby as hereinafter described. Each crate or framework C is illustrated as comprising a bottom portion to which are attached longitudinally and upwardly extending spaced portions forming a plurality of compartments for the plates P. As shown, the bottom portion of the crate or framework is formed by pairs of spaced transversely extending bars 22 to which vertically extending portions or walls 23 are attached. The walls 23 are preferably formed of plates provided with suitable openings to permit the free flow of the pickling solution therethrough and the ends of the crate or framework are open. Alternatively, the vertical plates or walls 23 may be replaced by vertically extending bars or by a combination of vertically and longitudinally extending bars if desired. Also, the bottom portion of the crate or framework may be formed by a plate or plates with or without openings if desired. The crates or frameworks C are preferably constructed of Monel metal or other suitable material which is resistant or inert to the pickling solution.

In the illustrated form of the crates or frameworks, six vertically extending members have been shown providing two side walls or members and four partition walls or members, thus forming five compartments for each framework. Obviously, a greater or lesser number of such wall members may be employed and in certain instances no partition walls are necessary. Also, the spacing between the vertical members or walls 23 may be varied and it is not necessary that all of the compartments have the same width. The width of the compartments is dependent upon the size of the plates to be treated, the number placed in each compartment and the amount of tilting or rocking which it is desired to impart to the plates. The width of the compartments is preferably less than the width of the plates P to be supported therein so that even if only a few plates are placed in a compartment they will be supported with their planes extending generally vertically. As shown in Fig. 2, the plates P are placed in the crate or framework in a manner such that they stand on edge and so that there is room for the plates to tilt about their lower edges or corners relative to the framework when the latter is rocked so that adjoining sides of adjacent plates strike and rub together and the outer plates in each compartment strike or rub against the members or walls 23 of the framework.

Preferably, the plates P are loaded into the crates or frameworks before the latter are placed in the tank A and the frameworks are then lowered into the tank so as to rest upon the transverse members 10 of the cradles B. This may be effected by providing a plurality of chains or other flexible supporting means 24 for each framework, the lower ends of the chains being attached to the crates or frameworks adjacent the corners thereof. The upper ends of the chains are free and are adapted to be engaged by hooks 25 supported upon transverse beams or members 26 which form a part of, or are attached to, a crane or the like, not shown. After a crate or framework has been positioned within the tank A, and rests upon the cradle as shown in Fig. 2,

the upper ends of its chains 24 are disconnected from the hooks 25 and the said upper ends of the chains may then be supported upon fixed hooks 27 fastened to the tank A adjacent the top thereof. The chains or cables 24 should have sufficient slack, when supported as shown in Fig. 2, so as not to interfere with the rocking and lifting movements of the crate or framework.

In order to effect movement of the cradles B and of the crates or frameworks C to produce tilting of the plates P, the shafts 17 and 18 are provided with a mechanism for effecting rocking thereof. As shown in Figs. 1 and 3 this rocking mechanism comprises arms 28 and 29 which are attached to the shafts 17 and 18, respectively, the outer ends of these arms being pivoted to the upper ends of links 30 and 31. The lower ends of the links 30 and 31 are pivoted to a crankpin 32 in the form of a short shaft 32 which is non-rotatably mounted in the outer ends of crankarms 33 and 34. The crank arm 33 has its inner end connected with a shaft 35 which is the output shaft of a speed reduction unit 36 driven by a motor 37. The inner end of the crank arm 34 is provided with a stub shaft 38 journaled in a bearing bracket 39 which, together with the motor and the speed reduction unit, are supported upon a suitable pier or pillar 40 adjacent one end of the tank A.

Referring to Fig. 3, it will be observed that when the shaft 35 is rotated, the crank arms 33 and 34 will cause the center of the common pivot for the links 30 and 31, that is, the crank pin or shaft 32, to describe a closed path which in this instance is a circle, indicated by broken lines and designated D. This will cause the links 30 and 31 to rock the arms 28 and 29 and hence the shafts 17 and 18, thereby rocking the cradle B and the framework or frameworks C. For the purpose of illustrating the motion imparted to the arms 28 and 29, and hence to each cradle and framework, four positions of the center of the common pivot 32, spaced 90° apart in its path, have been designated 1, 2, 3 and 4 and the corresponding positions of the arms 28 and 29 for each of these positions of the pivot 32 are indicated by broken center lines bearing corresponding numerals. It will be observed, therefore, that with the parts as shown in Fig. 3 the center of the common pivot of the links is at position 1 in its circular path D and the arms 28 and 29 correspondingly occupy positions 1. At this time the shafts 17 and 18 and the arms 15 and 16 attached thereto occupy the positions as shown in Fig. 2 so that the cradle B and the crates or frameworks C are substantially horizontal and disposed at their lowermost positions. When the center of the common pivot 32 of the links 30, 31 has moved to the position designated 2, the link 31 will have elevated the arm 29 slightly to its position designated 2 in Fig. 3, while the link 30 will have elevated the arm 28 a greater extent to its position 2. Consequently, the shafts 17 and 18 will be rocked different amounts so that the arms 15 and 16 are raised to different elevations corresponding to those of the arms 28 and 29, respectively. This results in the cradle B and the frameworks C being rocked or tilted within the tank and hence the plates P will tilt about their lower edges relative to their framework or crate C. The positions assumed by the crates or frameworks C and the positions of the plates P therein will, therefore, be substantially as illustrated in Fig. 7. Since

the plates P which are to be pickled generally are of appreciable thickness, they will be rocked or tilted about their corresponding longitudinally extending lower edges or corners P¹. Hence, adjacent sides or faces of the plates come into engagement and slide relative to each as the crates or frameworks move from the position illustrated in Fig. 2 to that illustrated in Fig. 7. Also, the outer plate at the right-hand side of each compartment will strike and/or rub against the adjacent partition wall 23. This relative sliding and/or striking of the plates together and with the partition walls loosens and/or removes scale or oxides thereon and ensures a thorough wetting and treatment of the plates by the pickling solution. As mentioned before, the amount of the tilting of the plates is dependent upon the width of the compartments in the cradles or frameworks C, and upon the size and number of plates supported in each compartment.

When the center of the common pivot 32 of the links 30, 31 has reached the position 3 in its circular path D, both the arms 28 and 29 will occupy their uppermost positions, designated 3 in Fig. 3, and at this time the cradle B and frameworks or crates C will be substantially horizontal and in their uppermost position within the tank A. As the cranks 33 and 34 continue to rotate, the center of the common pivot 32 of the links 30, 31 moves to position 4, thus moving the links 30, 31 and rocking the arms 28, 29 to their positions designated 4. Hence, the cradle B and crates C are now rocked or tilted in a reverse direction to that in which they were tilted when the center of the common pivot 32 was at position 2 so that the plates P have now been rocked or tilted relative to their framework or crate in the opposite direction to that in which they were previously rocked or tilted. The plates P now assume a position somewhat similar to that illustrated in Fig. 8, from which it will be seen that the plates P have now rocked or tilted about their other lower longitudinally extending edges or corners P² so that adjacent faces or sides of the plates have again moved or slid relative to each other and the outer plates at the left-hand side of each compartment has struck or rubbed against the adjacent wall 23. This rocking and lifting motion is continuously repeated so long as the motor 37 is in operation and consequently the plates P rock or tilt relative to their framework or crates C so that the said plates strike and rub against each other and the adjacent side walls or partition walls of the framework. As mentioned before, this facilitates the loosening of the scale upon the plates P and the entrance of the pickling fluid therebetween so that the plates may be completely treated in much shorter time than has heretofore been possible.

In Figs. 4 and 5 of the drawings is illustrated a modified form of apparatus embodying this invention. As in the preferred form of the apparatus, a pickling tank A is provided and adjacent the longitudinal sides of the tank, at spaced points therealong, are located pillars or piers 21, the upper ends of which support bearing brackets 20'. These bearing brackets are substantially the same as the bearing brackets 20 of the preferred form except that they do not overhang a portion of the tank. The bearing brackets 20' support the longitudinally extending shafts 17 and 18 which are provided with arms 15, 16, 28 and 29 as in the form of the apparatus illustrated in the Figs. 1 to 3. Also, as in the

previously described form of apparatus, the shafts 17 and 18 of the present form are actuated in the same manner by employing links 30, 31 which are pivoted together and driven by the motor 37 through the gear reduction unit 36 as was previously described.

The crates or frameworks C employed in this form of the apparatus are constructed in the same manner as the crates employed in the previously described embodiment. In the present embodiment, however, the crates or frameworks C do not rest upon a submerged cradle. Instead the bars 22 of the bottom portion of each framework or crate are provided with longitudinally extending pivot pins 41 each of which is adapted to be received between a pair of spaced upwardly extending ears 42 mounted in the bottom of the tank A when the crate or framework C is placed therein. In addition, the chains 24, which are attached to the bars 22, now have their upper ends received upon hooks 43 which are connected with a transversely extending member 44, there being at least two such transversely extending members for each crate or framework and preferably spaced adjacent the ends of the latter. The transversely extending members or bars 44 are each provided with a loop 45 adapted to be engaged by a crane or other lifting means for raising and lowering the crate or framework C relative to the tank A.

When each crate or framework C is positioned within the tank A as shown in Fig. 5, the pivot pins 41 are received between the ears 42 as previously mentioned and in addition, the lower surface of the bars or members 44 rest upon the upper surface of longitudinally extending bars 46 and 47. The transverse members or bars 44 are guided into proper position relative to the bars 46 and 47, when being placed thereon, by downwardly extending angular members 48 and 49 attached to the lower surface of the bars 44 and cooperating with the bars 46 and 47 to center the crate or framework C so that the pivot pins 41 are properly disposed within the ears 42. The bars 46 and 47 extend longitudinally adjacent to, but spaced from the upper surface of the tank A, and are pivotally connected, as by means of short links 50 and 51, to the arms 15 and 16 carried by the shafts 17 and 18.

In the construction just described, energization of the motor 37 causes the shafts 17 and 18, and hence the arms 15 and 16, to be rocked in the manner described with respect to the preferred embodiment. Hence, the longitudinally extending members or bars 46 and 47 are elevated and lowered varying amounts thereby causing rocking and lifting motion of the crates or frameworks C and the plates P supported therein, this motion being transmitted from the members 46 and 47 to the crates or frameworks by the transversely extending members 44 and the chains 24. Therefore, each crate or framework C is rocked about a longitudinal axis corresponding with the line extending through the pivot pins 41 and, in addition, the crate or framework is raised and lowered within the pickling bath, the ears 42 having a sufficient height so that the pivot pins 41 are not displaced therefrom during such movements. Consequently, substantially the same type of motion is imparted to the crates or frameworks C and the plates P in this form of the apparatus as was imparted to the crates and plates in the previously described embodiment.

In employing either form of the illustrated ap-

paratus the operation, briefly summarized, comprises supporting the plates P in upstanding relationship upon a surface with the plates immersed in a pickling solution and then rocking the supporting surface so as to cause the plates to tilt relative thereto about their lower corners or edges as axes and to strike and rub against each other. This repeated striking and rubbing as the plates tilt or rock facilitates the removal of scale thereon and the penetration of the pickling solution therebetween.

The operation as briefly summarized above may be advantageously effected by placing a plurality of plates P in upstanding relationship in one or more crates or frameworks, such as those disclosed in the drawings and as described above, which are so constructed that the plates may tilt about their lower edges P¹ and P² but cannot fall upon their sides. The width of the compartments in each crate or framework will, of course, depend upon the size and number of plates to be supported therein and the amount of tilting to be imparted to the plates. The plates should be loosely disposed in the said crate or framework to permit the desired amount of tilted action. With the plates so positioned, each crate or framework is then lowered into the pickling solution within the tank A until it is supported as shown in either Fig. 2 or Fig. 5 depending upon the form of apparatus employed. The motor 37 is then started, thus causing rocking, lifting and lowering of each crate or framework by virtue of the movement of the cradle B, or of the longitudinal members 46, 47, as the result of the operation of the links 30, 31, shafts 17, 18 and the arms connected therewith. After the rocking, raising and lowering of the frameworks and plates has continued for a sufficient period of time the motor 37 is stopped and the crates or frameworks are removed from the tank A by means of a crane or the like.

At various points in the specification and in the claims the articles treated in the pickling solution are referred to as plates. This term is used, and intended to be interpreted, in its generic sense as comprising any metallic member whose thickness is less than its width and is inclusive of sheets and other similar commercially known shapes.

While a preferred embodiment of the apparatus and one modification have been disclosed in considerable detail it will be readily understood that numerous variations may be made in the construction and arrangement of parts by one skilled in the art without departing from the basic concept underlying the invention. Therefore, it is to be understood that the invention is not considered as limited to the exact details of construction herein illustrated and described but only as required by the spirit and scope of the appended claims.

Having thus described my invention, I claim:

1. An apparatus for pickling metal plates comprising an elongated tank adapted to contain a pickling solution, a framework for supporting the plates to be pickled in upstanding relationship, the said framework including a bottom portion and a plurality of upwardly extending portions attached to said bottom portion in parallel spaced relationship, cradle means movably supported in said tank and having members thereof removably supporting said framework in said tank so that the plates supported by the framework are immersed in the pickling solution, and means for rocking said cradle means to thereby rock the

5

said framework transversely of said tank, thus causing the plates to tilt relative to said framework so that adjoining sides of adjacent plates are moved relative to each other.

10

2. A pickling apparatus of the type defined in claim 1 and in which the means for rocking said cradle means includes a pair of links, means operatively connecting the corresponding end of each link to transversely spaced points on said cradle means, means pivoting the other ends of said links together, and means for moving the common pivot of said links in a closed path.

15

3. An apparatus for pickling metal plates comprising an elongated tank adapted to contain a pickling solution, a framework for supporting the plates to be pickled, the said framework including a transversely extending bottom portion and a plurality of upwardly extending portions attached to said bottom portion in parallel spaced relationship to provide a plurality of longitudinally extending spaces in which the plates to be pickled are placed, the spacing between adjacent ones of the vertically extending portions being less than the width of a plate placed therein so that the plates are supported with their planes extending substantially vertically, means for removably supporting said framework in said tank so that the plates supported by the framework are immersed in the pickling solution, and means for repeatedly rocking said last-mentioned means to thereby rock said framework transversely of said tank, thus causing the plates to repeatedly tilt relative to said framework so that adjoining sides of adjacent plates are moved relative to each other.

20

4. A pickling apparatus of the type defined in claim 3 and further comprising means on the bottom portion of said framework cooperating with means on the bottom of the tank, when the framework is positioned in the latter, to provide a longitudinally extending pivotal axis for said framework.

25

5. An apparatus for pickling metal plates comprising an elongated tank adapted to contain a pickling solution, a framework for supporting the plates to be pickled in upstanding relationship within the pickling solution in said tank, the said framework including a transversely extending bottom portion and a plurality of upwardly extending portions attached to said bottom portion in parallel spaced relationship to provide a plurality of longitudinally extending spaces adapted to receive plates to be pickled, the spacing between adjacent ones of the vertically extending portions being less than the width of a plate placed therein so that the plates are supported with their planes extending substantially vertically, means on said bottom portion cooperating with means on the bottom of the tank when the framework is positioned therein to provide a longitudinally extending pivotal axis for said framework, and means for rocking said framework about its pivotal axis thus causing the plates to tilt relative to said framework so that adjoining sides of adjacent plates are moved relative to each other.

30

6. A pickling apparatus of the type defined in claim 5 and in which the means for rocking said framework includes a pair of spaced longitudinally extending shafts, transversely extending arms attached to said shafts and operatively connected with the said framework, a pair of links, one end of one link being pivotally connected with a transversely extending arm attached to one of said shafts and the corresponding end of the

other link being pivotally connected to a transversely extending arm attached to the other of said shafts, the other ends of said links being pivoted together, and means for moving the common pivot of said links in a closed path.

7. An apparatus for pickling metal plates comprising an elongated tank adapted to contain a pickling solution, a framework for supporting the plates to be pickled in upstanding relationship, the said framework including a transversely extending bottom portion and a plurality of longitudinally and upwardly extending portions attached to said bottom portion in parallel spaced relationship, means for removably supporting said framework in said tank so that the plates supported by the framework are immersed in the pickling solution, pairs of aligned spaced upstanding ears in said tank, longitudinally extending pivot pins attached to the bottom portion of said framework and adapted to be received between said spaced ears when the framework is positioned in said tank to thereby provide a longitudinally extending pivotal axis for said framework, and means for rocking said framework supporting means to thereby rock said framework about its pivotal axis thus causing the plates to tilt relative to said framework so that adjoining faces of adjacent plates are moved relative to each other.

8. An apparatus for pickling metal plates comprising an elongated tank adapted to contain a pickling solution, a framework for supporting the plates to be pickled including a transversely extending bottom portion and a plurality of upstanding and longitudinally extending portions attached to said bottom portion and adapted to support plates to be pickled in upstanding relationship, means for removably supporting said framework in said tank including a pair of spaced longitudinally extending members disposed adjacent the top of said tank, a plurality of transversely extending members adapted to rest upon said longitudinally extending members, means connecting said transversely extending members with the bottom portion of said framework, and means for raising and lowering said longitudinally extending members in a manner such that the said framework is rocked transversely of the said tank thus causing the plates to tilt relative to said framework so that adjoining sides of adjacent plates are moved relative to each other.

9. A pickling apparatus of the type defined in claim 8 and further comprising means on the bottom portion of said framework cooperating with means on the bottom of the tank, when the framework is positioned therein, to provide a longitudinally extending pivotal axis for said framework.

10. An apparatus for pickling metal plates comprising an elongated tank adapted to contain the pickling solution, a framework for supporting the plates to be pickled in upstanding relationship, the said framework including a transversely extending bottom portion and spaced upwardly and longitudinally extending portions attached to said bottom portion, a cradle for removably sup-

porting said framework in said tank so that the plates supported by the framework are immersed in the pickling solution, and means for supporting and rocking said cradle to thereby rock said framework transversely of said tank thus causing the plates to tilt relative to said framework so that adjoining sides of adjacent plates are moved relative to each other.

11. A pickling apparatus of the type defined in claim 10 and in which the means for rocking said cradle includes a pair of links, means operatively connecting the corresponding ends of each link to opposite sides of said cradle respectively, means pivoting the other ends of said links together, and means for moving the common pivot of said links in a closed path.

12. An apparatus for pickling metal plates comprising an elongated tank adapted to contain a pickling solution, a framework for supporting the plates to be pickled in upstanding relationship, the said framework including a transversely extending bottom portion and spaced upwardly and longitudinally extending portions attached to said bottom portion, a plurality of members extending transversely of said tank in spaced relationship to the sides and bottom of the latter and adapted to have the framework supported thereon, pairs of vertically extending members pivotally connected adjacent their lower ends to said transversely extending members adjacent the ends of the latter, and means for raising and lowering vertically extending members in a manner such that said transversely extending members and said framework are rocked transversely of said tank thereby causing the plates to tilt relative to said framework so that adjoining sides of adjacent plates are moved relative to each other.

13. A pickling apparatus of the type defined in claim 12 and in which the means for raising and lowering vertically extending members includes a pair of spaced longitudinally extending shafts, transversely extending arms attached to said shafts and pivotally connected with the said vertically extending members, a pair of links, one end of one link being pivotally connected with a transversely extending arm attached to one of said shafts and the corresponding end of the other link being pivotally connected to a transversely extending arm attached to the other of said shafts, the other ends of said links being pivoted together, and means for moving the common pivot of said links in a closed path.
